CLAIM

The ornamental design for a fishing lure body, as shown and described.

DESCRIPTION

FIG. 1 is a perspective view of a fishing lure body showing my new design;

FIG. 2 is a top plan view thereof;

FIG. 3 is a front elevational view thereof;

FIG. 4 is a right side elevational view thereof, the side opposite being a mirror image; and

FIG. 5 is a bottom plan view thereof.

The broken line showing of the fish hooks is for illustrative purposes only and forms no part of the claimed design.
